UNITED STATES PATENT OFFICE.

ANDREW N. RUSSELL AND BERNARD A. MALKIN, OF LACHINE, QUEBEC, CANADA, AS
SIGNORS TO THE PAPER AND TEXTILE MACHINERY COMPANY, OF SANDUSKY, OHIO.

SUCTION ROLL.

Application filed June 3, 1924, Serial No. 717,588. Renewed February 15, 1926.

This invention relates to new and useful improvements in suction rolls for paper making machines, and the object of the invention is to provide a suction roll which will be easily dismantled for repairs and inspection, and which will allow said dismantling to be done without breaking or interfering with the water-tight packing in the bearing between the suction roll and the suction box.

Another object is to provide a suction roll for paper making machines, which will allow easy and fine adjustments to be made in the sealing medium between the inner surface of the suction roll and the suction box.

A further object is to provide a roll of the class stated which will be economical and efficient in operation and maintenance.

In an illustrative embodiment of our invention shown in the annexed drawings, we provide a suction roll, within which is mounted the suction box. The roll is adapted for continuous movement at the same speed as the wire or felt of the paper making machine, and the suction box which is mounted within the roll is adapted to remain at all times in air-tight contact with the inner surface of the roll. Between the roll and the box, packing is provided to seal the box, and we have mounted the packing in channels, on the underside of which are mounted wedge-shaped members adapted to engage with other wedges secured to draw bars mounted in the channel guides formed in the suction box. The wedges may be attached to the channel guides. The draw bars or channels are moved in the longitudinal direction by means of adjusting screws.

The draw bars or channels rising on the wedges in the channel guides raise the packing until it contacts with the inner surface of the suction roll. The suction box is mounted on self-aligning water-tight bearings at each end of the roll, said bearings being so constructed that the suction box may be withdrawn without disturbing the water-tight packing in the bearings.

In the drawings:

Figure 1 is a longitudinal sectional elevation of the suction roll.

Figure 2 is an end view of the suction roll.

Figure 3 is a sectional elevation of the roll taken on the line 3-3, Figure 1.

Figure 4 is a sectional elevation taken on the line 4-4, Figure 1.

Figure 5 is an end elevation showing the draw bar adjusting means between the suction box and the roll.

Figure 6 is a sectional elevation taken on the line 6-6, Figure 5.

Figure 7 is a plan view of the adjusting means shown in Figure 5.

Figure 8 is a side elevation showing the channel adjusting means between the suction box and the roll.

Referring more particularly to the drawings, 11 designates a suction, couch or press roll, the end castings 12 and 13 of which are secured to the roll by means of the screw bolts 14. The end casting 12 is provided with an outwardly extending portion 15 which forms a journal, which rotates in the bearing 17 mounted on the frame 18 of the machine in any suitable manner. The end casting 13 is also provided with an outwardly extending portion 19, which forms a journal which rotates in the bearing 20, also mounted in the frame 18. The bearings are provided with the necessary water-tight packings 21 and lubricating means 22. Within the roll is mounted the suction box 23, one end of which is mounted on the end 24 of the suction pipe 25, which passes through an aperture 25^a formed in the journal end 15. As the roll rotates around the pipe, a self-aligning ball bearing 26 is mounted between the pipe and the end casting 12, which is provided with an inwardly extending portion adapted to form a housing 27 to engage with the outer face of the ball bearing. A shoulder 28 may be provided to position the bearing on the pipe and a cap 29 having water-throwing edges 30 may be secured to the housing 27 to protect the bearing. Grooves 31 may be formed in the journal 15 and water-tight packing rings 32 may be inserted in the grooves to form a water-tight joint between the pipe and the journal. A collar 33 may be attached to the bearing for supporting the outer end 34 of the pipe and positioning said suction box and holding it in any angular position. An elbow 35 is secured to the end

85

90

95

100

34 of the pipe by means of the hinged bolts 36, which engage with the lugs 36^a formed in the elbow. The elbow may be connected to a vertically disposed drain pipe 37 by 5 means of the slip coupling 38. The shower pipe 39 passes through the centre of the pipe 25 and through a bearing 41 formed in the elbow. A gland 40 may be fitted into a recess 42 having a ring of sealing material 43 to seal the bearing formed in the elbow. The other end 44 of the suction box 10 may be provided with a recess 45 adapted to receive the shaft 46, one end of which is secured to the journal 19 by any suitable 15 means. A sleeve 47 is mounted on the shaft 46 and a self-aligning bearing 48 is placed between the sleeve and the wall of the recess 45, a shoulder 49 being provided to position said bearing. To protect the bearing 20 from dirt, ooze, or water, a cap 50 is secured to the end of the suction box, and packing rings 51 may be inserted in the groove 52 formed in the cap, said packing forming a sealing medium for the bearing. A guard 25 30 35 40 45 50 55 60 65 70 75 80 85 90 95 100 105 110 115 120 125 130

Figures 3 to 7 inclusive are devoted to the details of the sealing means between the wall of the roll and the upper edges of the suction box, which are provided with the 35 channel guides 55. Slidably mounted in the guides are the draw bars 57^a having the wedges 57 secured thereto. The channels 58 are mounted in the guides and wedges 58^a adapted to engage with the wedges on the 40 draw bars are secured to the channels. Packing strips 59 are placed in the channels to form a sealing medium between the roll and the suction box. Bearings 62 may be formed in the suction box and adjusting screws 61 45 50 55 60 65 70 75 80 85 90 95 100 105 110 115 120 125 130

may be rotatably mounted therein and held from longitudinal movement by means of the collars 64. The threaded portions 65 of the screws engage with threaded lugs 60 riveted or otherwise secured to the draw 50 55 60 65 70 75 80 85 90 95 100 105 110 115 120 125 130

bars mounted in the channel guides, so that on turning the screws the channels are raised or lowered on the wedges, thereby regulating the sealing means between the packing and the inner wall of the roll. The 55 suction box is sealed at its end by means of the adjustable packing heads 67, which are mounted on the screws 66. The screws are rotatably mounted in the heads 67 and are held in position by means of the collars 60 65 70 75 80 85 90 95 100 105 110 115 120 125 130

70. The threaded portion 68 of the screws engages with the threaded eye bolt 69 secured to the suction box, so that on movement of the screws, the heads are moved towards or away from the eye bolt 69. The 65 upper surface of the box is provided with

apertures or perforations 71, which allow water abstracted from the sheet to pass to the bottom 72 of the box, said bottom being tapered towards the drain pipe end of the box to assist in draining off the water. 70

In Figure 8 we have shown a modification in which the wedges 58^a are formed in the channel guides 55^a, and the threaded lugs 60^a are secured to the channels. By rotating the screw 61, the channels rise or fall 75 on the wedges formed in the guides. Various other modifications may be made without departing from the spirit of the invention. 80

In operation, the packing heads are adjusted by means of the screws 66 to suit the width of the pulp sheet carried by the wire or felt of a paper making machine. The roll rotates in the bearings mounted on the frame and the suction box remains stationary and in contact with the inner wall of the roll. To reduce the frictional resistance between the suction box and the roll, self-aligning ball bearings are placed between them. The packing medium between the suction 85 90 95 100 105 110 115 120 125 130

rolls and the suction box is very easily adjusted, being mounted in channels which are mounted on wedge shaped members secured to the underside and adapted to engage with the wedges of the draw bar, which is 95 100 105 110 115 120 125 130

slidably mounted in the channel guides formed in the suction box. The screws are rotatably mounted in the box and, when turned, raise the packing strips to seal the joint between the box and the roll by pulling the draw bar and causing the sealing medium channels to ride up the inclined side of the wedges on the underside of the channel. The roll is very easily dismantled for repairs or inspection. The screw bolts 105 110 115 120 125 130

14 are loosened, leaving the end casting 12 free. The joints in the drain pipe are then loosened and the suction box can then be withdrawn without interfering with or loosening of the packing rings between the 110 115 120 125 130

journal 15 and the drain pipe. The watertight joint between the sleeve 47 and the cap 50 is not interfered with as said sleeve is withdrawn from the suction box. In erecting the device, the suction box is placed 115 120 125 130

within the roll and the shaft 46, being tapered, enters the sleeve easily and gradually raises the suction box into position. This arrangement greatly reduces the cost of maintenance and facilitates the operation 120 125 130

of dismantling and re-erecting the suction box. In the modification, the channel with the packing mounted therein is raised by pulling it along the guides, adjusting screws being provided for this purpose. The 125 130

wedges on the underside of the channels engage with the wedges formed in or secured to the box. The channel when pulled longitudinally raises the packing upwardly to seal the box. 130

Having thus described our invention, what we claim is;—

1. In a carrier roll for paper making machines or the like, a roll, means for rotatably supporting said roll, a suction box mounted within the roll, guides formed in the suction box, channel-shaped members mounted in the guides, packing or sealing means within the channel members and adapted to contact with the roll, wedges secured directly to the underside of the channels, wedges mounted in the guides and adapted to engage with the channel wedges, and means connected to one set of the wedges so that on movement 10 of same the channels will rise or fall in the guides.

2. In a suction, couch or press roll for paper making machines, a roll, means for rotatably supporting said roll, a suction box 20 mounted within the roll, channel guides formed in the upper edges of the suction box, channels mounted in the guides, wedges secured directly to the underside of the channels, draw bars mounted in the channel 25 guides, wedges secured to the draw bars and adapted to frictionally engage with the wedges on the underside of the channels, sealing means between the channel and the roll, and screw adjusting means secured to 30 the suction box and adapted to engage with the draw bar to raise or lower the sealing means through the medium of the wedges.

3. In a suction roll for paper making machines or the like, a roll, means for rotatably supporting said roll, a suction box mounted within the roll, channel guides formed in the suction box, channels mounted in the guides, sealing means between the channels and the roll, wedge type adjusting means 40 between the channel guides and the channels for positioning the said sealing means, means secured to the suction box for operating said wedge type adjusting means, anti-friction bearings between the roll and the 45 suction box, sealing means for said anti-friction bearings, and means to allow withdrawal of the suction box without interfering with or damaging the sealing means for the bearings.

50 4. In a suction, couch or press roll for paper making machines, a roll, detachable journals at the ends of said roll, bearings for rotatably supporting the journals, a suction box mounted within the roll, sealing means between the suction box and the roll, a self-aligning anti-friction bearing between one end of the suction box and the roll journal, sealing means for the self-aligning bearings and the journals, a shaft secured to 55 one of the journals, of the roll adapted to support the other end of the suction box, a sleeve mounted on said shaft, an anti-friction bearing between the sleeve and the suction box, sealing means for the last mentioned 60 55 anti-friction bearing, and means formed in

the shaft to allow easy withdrawal and erection of the suction box without interfering with any of the sealing means.

5. A suction roll comprising, in combination, a roll having a detachable head; a suction box in the roll having a tubular member extending through said detachable head; bearings between the roll and suction box rotatably supporting one from the other; one of said bearings carried by said detachable head, the other bearing being carried by an end of the suction box, and a spindle removably inserted in the other bearing detachably connecting the opposite head of the roll with the corresponding end of the suction box; whereby the roll and suction box may be separated one from another without disturbing said bearings upon unfastening said detachable head.

6. The combination of a suction roll 85 equipped with detachable heads carrying the roll journals, a suction box mounted within the roll and provided with a recess at each end, a drain pipe passing through one of the heads and its journal, and having its inner end entered into one of the recesses of the suction box to provide a support therefor, a sealed ball bearing interposed between the drain pipe and an inwardly extending portion of the said head, an inwardly projecting spindle carried by the remaining head, and a sealed ball bearing contained in the remaining recess of the suction box and adapted to fit upon the spindle in separable engagement therewith.

7. A suction roll comprising, in combination, a roll; a suction box therein; annular roller bearings interposed between the roll and box rotatably supporting one from the other; said roll having a detachable head carrying one of said bearings; the opposite bearing being carried by the box, and the opposite head of the roll having an inwardly protruding spindle removably inserted in said opposite bearing, substantially as and for the purpose described.

8. A suction roll comprising, in combination, a roll having journals including a detachable tubular journal; a stationary suction box in the roll having a pipe extension through said detachable tubular journal; the opposite journal having a coaxial spindle projecting toward said tubular journal into the roll; and annular roller bearings at opposite ends of the box supporting it on said pipe extension and spindle; both of said bearings being permanently associated with the box, and the said inwardly projecting spindle being removably inserted in the bearing at the end of the box opposite said pipe extension, whereby the box may be withdrawn from the roll with the said detachable journal and with the said bearings.

9. A suction roll comprising, in combination, a roll; a suction box therein having a

pipe extending through one end of the roll; said box adapted to be withdrawn from the roll through said end; said roll having an inwardly protruding spindle at its opposite 5. end; roll supporting bearings; means supporting said pipe extension and thereby supporting the box at one end; and means comprising an annular roller bearing carried by the opposite end of said box, into which said 10 spindle is removably inserted, supporting said opposite end of the box from and within the roll.

10. A suction roll comprising, in combination, a roll having reduced tubular journals, 15 roll supporting structures having bearings for said journals, a stationary suction box

in the roll having packings engaging the interior surface of the roll, members extending from opposite ends of the suction box into said tubular journals, at least one of said 20 members providing a pipe connection with the suction box, means supporting the suction box in proper relation to the roll through said members, means for regulating the pressure of the suction box packings on 25 the interior surface of the roll, and means for angularly adjusting the position of the suction box.

In witness whereof, we have hereunto set our hands.

BERNARD A. MALKIN.
ANDREW N. RUSSELL.
